UNITED STATES PATENT OFFICE

136,606

DESIGN FOR A BONNET

Iva M. Christensen, Mayfield, Utah

Application July 27, 1943, Serial No. 110,774

Term of patent 7 years

To all whom it may concern:

Be it known that I, Iva M. Christensen, a citizen of the United States, residing at Mayfield, in the county of Sanpete and State of Utah, have invented a new, original, and ornamental Design for a Bonnet, of which the following is a specification, reference being had to the accompanying drawing, forming part thereof.

I claim:

The ornamental design for a bonnet, as shown.

IV A M. CHRISTENSEN.
